AWNNG

Jerry H. O'Brien, Wichita, Kans.

Application October 10, 1949, Serial No. 5,408

Term of patent 14 years

(Cl. D14—6)

To all whom it may concern:

Be it known that I, Jerry H. O'Brien, a citizen of the United States, residing at Wichita, county of Sedgwick, State of Kansas, have invented a new, original, and ornamental Design for Awning, of which the following is a specification, reference being had to the accompanying drawing, forming a part hereof.

Fig. 1 is a front elevational view of the awning in fully opened position.

Fig. 2 is a front elevational view of the same in closed position.

Fig. 3 is a side elevational view of the awning in closed position.

Fig. 4 is an isometric view of the awning in fully opened position.

Fig. 5 is a side elevational view of the awning in fully opened position.

I claim:

The ornamental design for an awning, as shown.

JERRY H. O'BRIEN.
